SCISSORS OR SIMILAR ARTICLE

Stephen J. Gorel, Stratford, Conn.

Application May 16, 1955, Serial No. 35,997

Term of patent 7 years

(Cl. D22—5)

Fig. 1.

Fig. 2.

Fig. 1 is a side view of a scissors or similar article, showing my new design, and

Fig. 2 is an edge view thereof.

The side opposite to that shown in Fig. 1 presents a similar appearance as the side shown and the essential features of the design reside in the portions shown in solid lines on the drawing.

I claim:

The ornamental design for a scissors or similar article, substantially as shown and described.
